UNITED STATES PATENT OFFICE.

MICHAEL BECK, OF MINNEAPOLIS, MINNESOTA.

CONTINUOUS-COMBUSTION TURBINE.

SPECIFICATION forming part of Letters Patent No. 698,895, dated April 29, 1902.

Application filed October 6, 1900. Serial No. 32,229. (No model.)

To all whom it may concern:

Be it known that I, MICHAEL BECK, a citizen of the United States, residing at Minneapolis, in the county of Hennepin and State 5 of Minnesota, have invented certain new and useful Improvements in Continuous-Combustion Turbines; and I do hereby declare the following to be a full, clear, and exact description of the invention, such as will enable 10 others skilled in the art to which it appertains to make and use the same.

My present invention has for its object to provide an explosive-engine in the nature of a turbine having high efficiency and adapted 15 for various uses—such, for instance, as for driving bicycles, automobiles, and launches.

To this end my invention consists of the novel devices and combinations of devices hereinafter described, and defined in the 20 claims.

The invention is illustrated in the accompanying drawings, wherein like characters indicate like parts throughout the several views.

Figure 1 is a view, partly in side elevation and partly in vertical section, some parts being broken away and others being removed, showing my improved turbine applied to drive one of the wheels of a bicycle or automobile. Fig. 2 is a transverse vertical section on the 25 line $x^2 x^2$ of Fig. 1, some parts being broken away. Fig. 3 is a vertical section on the line $x^3 x^3$ of Fig. 2, some parts being broken away and others removed. Fig. 4 shows portions of a co-operating pair of propelling-plates or 30 blade-wheels, said members being shown as separated and turned faces up. Fig. 5 is a plan view of the parts shown in Fig. 4, shown as in parallel planes, but as separated. Fig. 6 is a detail in plan of one of the pump-pis- 35 tons; and Fig. 7 is a detail in vertical section, taken through the spindle or axle of the turbine, on the line $x^7 x^7$ of Fig. 2.

This rotary turbine is designed to be run by the burning or continuous explosion of a 40 mixture of oil, such as gasolene, with water and air. In the illustration given the oil and water are contained, respectively, in the inner and outer compartments 1 and 2 of an ele- 45 vated tank 3, which is suitably supported by 50 means not shown. The tank 3 is provided with a needle-valve 5, which controls the dis- charge of oil and water from the respective

compartments 1 and 2. The head of said valve has a longitudinal passage 6 for the dis- charge of the oil, the upper end of which pas- 55 sage is closed when the needle-valve is screwed downward. The oil and water are dropped directly into or through the funnel-head 7 of a delivery-pipe 8, and the said funnel is pro- 60 vided with air-inlet passages 9 at various points.

The delivery-pipe 8 in the construction illus- trated has prongs 8', which run to and con- 65 nect with the opposite ends of a non-rotary spindle 10, of tubular form, plugged at 11 in- ward of its ends. At its central portion the spindle 10 is formed with an enlargement 12, which has a plurality of radial passages 13, that extend in the same plane at right angles to the axis of the spindle. Other passages 14 70 radiate obliquely from the central passage of the spindle 10 and open at the sides of the enlargement 12. A large sleeve or hub 15 is loosely mounted on the spindle 10 and the en- 75 largement 12 thereof, the ends of the same serving as cylinders in which reciprocating pump-pistons 16 are mounted to reciprocate, as presently described. The hub 15 is pro- 80 vided at its central portion with a pair of heavy disks or propelling-plates 17, that are spaced apart laterally to form an attenuated 85 annular chamber 18, which is in constant com- munication with the radial passages 13, here- 90 tofore noted. An annular case or shell 19 is rotatively mounted, as shown, by ball-bear- 95 ings 20 on the ends of the spindle 10. At its periphery the rotary case 19 is formed with a large driving-sheave 21, which is adapted to frictionally engage with the pneumatic tire 22 of a bicycle or automobile.

In the construction illustrated the means for attaching the device to a bicycle or auto- 100 mobile has been omitted, as the same forms no part of my present invention. However, in Figs. 1 and 2 the delivery-tube 8' is shown as extended through a hollow fork 23, pro- 105 vided at the ends of its prongs with lugs 24, to which the spindle 10 is secured against ro- 110 tation, as shown, by means of bearing-cones 25 and clamping-nuts 26, applied at each end 115 of the spindle.

The pump-pistons 16, already noted, are mounted for sliding movement, as shown, by key and splined connections 27 on the non-

rotary spindle 10, and they are provided with cam-grooves 28, with which coöperate cam-pins 29, carried by the hub or cylinder-sleeve 15. Spring-held check-valves 30 control passages 31, extending through the piston 16. Spring-pressed check-valves 32, which are mounted on the spindle 10, close to its enlargement 12, coöperate with valve-seats 33, formed within the cylinder-hub 15.

10 In addition to the propelling-plates 17 the hub 15 carries other annular plates 34 and 35, the hubs of which are screw-threaded thereon and are adapted to be locked in their proper adjustment by lock-nuts 36.

15 The rotary case 19 is provided on each side of its center with annular propelling-plates 37 and 38, which are adapted to be adjusted laterally and secured wherever set by set-screws 39, which set-screws impinge upon the 20 adjacent peripheral portions of said plates and are adapted to hold the same wherever set.

The propelling-plates 17, 34, 35, 37, and 38 are provided with ports or passages 40, through 25 which the motive fluid will pass, as indicated by the several arrows marked on Fig. 2. 40' indicates exhaust-ports in the hub of the rotary case 19, and 10' indicates admission-ports in the spindle 10. The several propelling-plates 17, 34, 35, 37, and 38 are formed 30 with concentric V-shaped or outwardly-tapered ribs, which are cut obliquely, as best indicated in Figs. 4 and 5, to form annularly-arranged series of V-shaped or pointed propelling-blades 41. In Fig. 2 the ribs from 35 which the propelling-blades are cut are shown in solid section for the purpose of clearness, and in Figs. 4 and 5 the said propelling-blades are shown as cut only for a short distance. It will, however, be understood, of 40 course, that these propelling-blades will be cut completely around the said flanges. It will also be understood that the coöperating blades of adjacent propelling-plates are inclined in reverse directions.

45 With the V-shaped or pointed propelling-blades arranged as above described adjustments to compensate for wear or for other reasons may be made between the running edges of the said blades by laterally adjusting the propelling-plates. In other words, the clearance between the propelling-blades of the propelling-plates may be varied at will.

50 55 As an igniter I provide a pair of electrodes 42, which are passed axially through the spindle 10 and terminate in close proximity at the junction of the several radial passages 13. These electrodes 42 are by wires 43 connected in an electric circuit involving, usually, the secondary of an induction-coil and a key or device for making and breaking the circuit to produce a spark between the electrode whenever desired in a manner well understood and not necessary for the purposes of this case to illustrate.

The operation will be substantially as fol-

lows: The water and oil dropping from the tank 3 when the needle-valve 5 is moved into an open position will strike a sharp dividing 70 edge 8" at the junction of the feed-tube branches 8' and will run into both ends of the fixed spindle 10 and from thence through the admission-ports 10' into the outer ends of the cylinders formed by the rotary hub or 75 sleeve 15. Under the rotary movement of the said hub 15 the cam-pins 29, acting on the cam-grooves 28, will reciprocate the pump-pistons 16 in reverse order. When the pistons 16 move outward, their check-valves 30 are opened, so that the motive fluid, which is at this time a liquid, is forced through the 80 passages 31 to the inner ends of the cylinders. Then under the inward movement of the said pistons the large check-valves 32 are forced 85 open, and the liquid is forced through the feed-passages 14, into contact with the slightly-separated points of the electrodes 42. As the pistons operate in reverse order, a continuous flow of the combustible liquid is afforded. 90 This combustible liquid is ignited by producing a spark between the electrodes, and the said liquid is then converted into a gas, which rushes violently out through the radial 95 passages 13 into the attenuated chamber 18, formed between the propelling-plates 17 of the rotary cylinder-forming hub or sleeve 15. From the chamber 18 the expanding gas mixed with steam formed from the water intermixed with the combustible fluid rushes 100 outward through the ports 40 and between the propelling-plates 17, 34, 35, 37, and 38, taking the various paths indicated by the arrows marked on Fig. 2, and finally is exhausted at very low pressure through the exhaust-parts 40'. In taking the courses indicated by the said arrows marked on Fig. 2 the expanding gas causes the hub or sleeve 15, with its propelling-plates 17, 34, and 35, to rotate in one direction and the rotary case 110 115 or shell 19, with its propelling-plates 37 and 38 and sheave 21, to rotate in the opposite direction. In this connection attention is called to the fact that the hub or sleeve 15 is limited in its speed of rotation by the resistance offered by the pump-pistons 16, which are reciprocated thereby. In fact, the pumps act in a sense as governors. When the driving 120 resistance put upon the case 19 and sheave 21 is increased, so as to decrease the speed thereof, the hub member 15 will tend to run at a higher rate of speed and to correspondingly increase the speed of the pumps; but the increasing resistance offered by the pump-pistons will increase the base of reaction for 125 the engine.

The above is my theory of the operation. What I claim, and desire to secure by Letters Patent of the United States, is as follows:

1. The combination with a rotatable member carrying means for transmitting power, of a second reversely-rotatable member freely rotatable with reference thereto, a pump for supplying motive fluid carried and actuated 130

by said second member and serving as a sole base of reaction therefor, each member having alternately-arranged plates carrying propelling-blades, the plates of the one member being interposed between those of the other.

5 2. In a rotary engine, the combination with a fixed hollow spindle, of a pair of reversely-rotatable members mounted on said spindle, the one embracing the other, said members having alternated propelling-plates with co-operating propelling-blades, a pair of pumps having pistons working within the hub of the inner member, means for sliding said pistons

on said spindle under the rotary movement of the said inner rotary member, means for supplying motive fluid to the ends of said spindle, and from thence to the pumps, and means for transmitting power from the outer rotary member, substantially as described.

15 In testimony whereof I affix my signature 20 in presence of two witnesses.

MICHAEL BECK.
